UNITED STATES PATENT OFFICE

MONROE S. CLAWSON, OF UPPER MONTCLAIR, NEW JERSEY

COLLAPSIBLE LAMP SHADE

Application filed January 17, 1927. Serial No. 161,579.

This invention relates to lamp shades and has for its general object the provision of a lamp shade designed particularly for use in therapeutic work and so constructed as to be collapsible and therefore convenient to pack and carry when not in use.

An important object of the invention is to provide a lamp shade so constructed as to embody a plurality of connected panels which will act to distribute light in a more efficient manner than can be accomplished by means of shades of the ordinary type, it being desirable to avoid concentration at too limited an area.

Another object of the invention is to provide a collapsible lamp shade having novel means whereby it may be held in assembled or set up position and easily clamped upon any ordinary or preferred electric light socket without the necessity for employing any special tools or altering the construction of the socket itself.

Another and more specific object is to provide a collapsible lamp shade embodying a plurality of panels pivotally connected in a manner similar to the connection of the leaves of hinges by means of permanently mounted pintles, the arrangement being such that the shade will collapse into substantially flat condition when it is detached from the socket and the securing clamp removed, the provision of interfitting knuckles on the leaves leaving slots which will act to insure ventilation and prevent excessive heating of the parts and the throwing of heat, by reflection, onto the area illuminated by the lamp in connection with which the shade is used.

A further object is to provide a shade of this character in which one of the pintles connecting the panels may be removable to permit collapsing in a different manner.

An additional object of the invention is to provide a collapsible lamp shade of this character for the above or an analogous purpose which will be simple and inexpensive to manufacture, easy to set up or apply and use, positive in action, efficient and durable in service, and a general improvement in the art.

With the above and other objects and advantages in view, the invention preferably

consists in the arrangement and combination of parts and detailed structural features to be hereinafter more fully described and claimed, and illustrated in the accompanying drawings in which:

Figure 1 is a view partly in side elevation and partly in vertical section showing the shade applied to an incandescent lamp and its bulb,

Figure 2 is a top plan view with parts broken away and in section,

Figure 3 is a view showing the preferred form of shade removed and collapsed into flat form,

Figure 4 is an edge elevation thereof,

Figure 5 is a detail view showing one form of clamp,

Figure 6 is a similar view showing a modified clamp, and

Figure 7 is a plan view illustrating a modified form of shade.

Referring more particularly to the drawings and especially Figures 1 to 6 the letter A designates an ordinary incandescent lamp socket and B designates the lamp or bulb mounted therein in the usual manner.

In carrying out the invention I provide a shade designated as a whole by the letter C, which shade is formed of a plurality of panels or sections 10 which may be constructed of any suitable material but which are preferably made of metal on account of the non-breakability thereof and for convenience in manufacture as being more easily workable than certain other materials. The sections 10 are all preferably of the same shape and each is disclosed as substantially triangular or trapezoidal. Each section is provided at its smaller end with a reduced extension 11 which is offset angularly with respect to the panel so that when the shade is in assembled position and applied to a lamp socket as shown in Figure 1 these extensions 11 will extend vertically in parallel relation whereas the panels themselves will flare outwardly and downwardly. The extensions 11 have their extremities bent outwardly and downwardly to define hooks 12 which cooperate with clamping means to be described for effecting securing upon the

100

socket A. The side edges of the sections or panels are formed with interfitting knuckles 13, as is common in hinge structures, and pivotal connection is effected by means of 5 pintles 14 so that the shade may be collapsed into the condition shown in Figures 3 and 4.

In the actual manufacture of the sections or panels, the formation of hinge knuckles such as those disclosed leaves slots 15 which 10 are necessary for clearance and these slots will provide adequate means, when the shade is assembled and in use, for insuring ventilation so that overheating of the parts and reflection of heat onto the area or objects 15 illuminated by the lamp will be avoided, or at least minimized.

For securing the shade upon the socket, use is made of a clamp which may conveniently be either that shown in Figure 5 or that disclosed 20 in Figure 6. In the first mentioned instance the clamp 16 is represented as being a split metal band of a resilient nature having apertured ears 17 for the passage of a bolt 18 equipped with a nut 19. The clamp 25 is of such size as to engage outwardly of the extensions 11 and beneath the hooks 12 as clearly indicated. In the latter instance the clamp is shown as formed of two sections 20 pivoted at 21 and having terminal ears 22 through which passes a bolt 23 carrying a nut 24. This modified form of clamp is applied and used in the same manner as the first described form.

In the use of the device, assuming that it 35 is in collapsed or knocked-down condition as shown in Figures 3 and 4, it is merely necessary to unfold the superposed halves of the shade, (each consisting in the present instance of four panels, though there is no limitation 40 as to the number) and arrange the device in frusto-pyramidal or conical form. The preferred clamp is then expanded or opened up and slipped over or about the extensions 11 and beneath the hooks 12. The assembled 45 extensions carrying the clamp are then slipped onto the socket A and the bolt 18 or 23, as the case may be, inserted through the ears of the clamp and the nut applied and tightened to obtain the necessary clamping action.

50 In Figure 7 I have shown a modified form of the invention in which the panels are connected by pintles 25 and 26 the former being permanent and upset at both ends and the latter being removable so that the shade may be collapsed. Of course any desired number of the pintles may be removable but one is probably sufficient.

In the use of this form of the device, assuming 55 that it is in knocked-down or collapsed condition as shown in Figure 7, it is merely necessary to pivot or swing the various sections by bringing the edges of the two end-most sections together with the knuckles thereon interfitting, subsequent to which the removable pinte 26 is inserted through these

knuckles to provide the necessary connection. The clamp, regardless of which is used, is applied as explained above. In both forms of the invention it will be seen that as the clamp engages within the hooks the shade 70 cannot drop down with respect to the socket and lamp but will be positively maintained in the proper or operative position. The shade will of course act in substantially the same manner as any other except that it has the 75 advantages of insuring ventilation and distributing the light, the latter feature being the result of having the plurality of flat panels or sections each of which has its own separate reflecting action. To effect removal 80 and collapsing of either form of the shade, the reverse operation to that described is followed in an obvious manner.

From the foregoing description and a study 85 of the drawings it will be apparent that I have thus provided a simply constructed, inexpensive and highly convenient shade which may be readily carried about from place to place without danger of breaking and used wherever necessary. These features recommend 90 the device to physicians, surgeons or others engaged in therapeutic work. It is believed that the construction, operation and advantages will be readily apparent to one skilled in the art without further explanation.

While I have shown and described the preferred embodiments of the invention, it should be understood that the disclosure is merely for the purposes of illustration as the right is reserved to make all such changes in the shape, size, number of parts and other mechanical details as will not depart from the spirit of the invention or the scope of the claims hereunto appended.

Having thus described the invention, I claim:

1. A collapsible lamp shade comprising a plurality of sections provided at one end with reduced extensions adapted to engage upon an electric lamp socket in embracing relation thereto, and means engageable exteriorly about said extensions for clamping the same rigidly and immovably to the socket.

2. A lamp shade comprising a plurality of similar sections hingedly connected at their adjacent side edges whereby the shade may be collapsed into flat form when not in use with one half lying on the other in face to face relation, and means for clamping the assembled sections upon an electric lamp socket.

3. A collapsible lamp shade comprising a plurality of similar panels of substantially trapezoidal shape hingedly connected at their adjacent side edges, extensions formed on the panels at the smaller ends thereof and terminating in hooks, said extensions being adapted to be engaged in embracing relation upon an incandescent lamp socket, and means engaging exteriorly of the extensions and

within said hooks for holding the shade rigidly upon the socket.

4. A lamp shade comprising a plurality of similar panels of substantially trapezoidal shape hingedly connected at their side edges, extensions formed on the panels at the smaller ends thereof and terminating in hooks, said extensions being adapted to be engaged in embracing relation upon an incandescent lamp socket, and means engaging said hooks for holding the extensions upon the socket, comprising a clamp engaging within the hooks and extending outwardly about said extensions, the shade being collapsible with one half the sections lying upon the other half with the inner surfaces of both halves face to face.

5. A collapsible lamp shade comprising a plurality of trapezoidal shaped sections hingedly connected at their adjacent side edges, one hinge connection being removable whereby the shade may be flattened out when not in use, extensions at the smaller ends of the sections, and means engaging said extensions for clamping the same upon an incandescent lamp socket.

6. A lamp shade comprising a plurality of panels hingedly connected at their side edges, and means connected with the panels at the upper ends thereof for clamping the shade upon an electric lamp socket, the shade being collapsible with one half the sections lying upon the other half with the inner surfaces of both halves face to face.

35 In testimony whereof I affix my signature.
MONROE S. CLAWSON.
